INFANT'S TOILET SEAT

Richard C. Lewis, Winnetka, Ill.

Application August 19, 1944, Serial No. 550,271

2 Claims. (Cl. 4—239)

My invention relates to an infant's toilet seat adapted to be removably attached to a conventional toilet seat.

The prevailing type of detachable infant's toilet seats have metal parts, hooks, studs, staples, with rough corners and edges that scratch toilet seats on which they are placed. They are also complicated in structure, and difficult to get on and off the conventional seat.

It is among the objects of this invention to solve these problems and to provide an infant's toilet seat that will not scratch, wear, or mar the seat on which it is placed. My construction is simple and eliminates complicated parts, is easy to place in use and to remove from the conventional seat. My seat is safe and cannot slip out of position in use and injure the child.

My invention also contemplates such other objects, advantages and capabilities as will later more fully appear and which are inherently possessed by my invention.

While I have shown in the accompanying drawing a preferred form of my invention, yet I wish it understood that the same is susceptible of modification and change without departing from the spirit of my invention.

Referring to the drawing, Fig. 1 is a top plan view of my device; Fig. 2 is a perspective bottom view of the same; Fig. 3 is a sectional view on line 3—3 of Fig. 1; Fig. 4 is an end elevational view of my device being applied to a larger conventional seat; Fig. 5 is an end elevational view of my device in place on a conventional seat and Fig. 6 is a side elevational view of my device.

The embodiment selected to illustrate my invention comprises a seat 10 having a substantially central opening 11 and a front slot 12 communicating therewith.

Hingedly attached to the undersurface 13 of said seat 10 are a pair of spaced holding or gripping members 14. In my preferred form illustrated herein I provide an upper hinge 15 having a portion 16 attached to the undersurface 13 adjacent one side of the upper portion of opening 11, and a lower hinge 17 having a portion 18 attached to the undersurface 13 adjacent a lower portion of opening 11. Each of said hinges has a portion 19 on the other side of hinge pin 20 attached to opposite extremes of the upper surface of upper portion 21 of one of the holding members 14. There are also similarly spaced upper and lower hinges 15 and 17 each having a portion 18 attached to the undersurface 13 adjacent the other side of upper and lower portions of opening 11, and each having

a portion 19 on the other side of hinge pin 20 attached to the opposite extremes of the upper surface of upper portion 21 of the other of the holding members 14.

In each of the holding members 14 the upper portion 21 extends diagonally upwardly and outwardly from the upper hinge 15 and diagonally downwardly and outwardly from the lower hinge 17 to rounded portions 22 on opposite ends of its outer edge 23. When the holding members 14 are moved against the undersurface of seat 10, their outer edges 23 extend slightly beyond the outer edges of seat 10.

Each of said holding members 14 has a middle portion 24 attached to the undersurface of upper portion 21 beginning at the inner edge 25 thereof, extending outwardly and ending in a curved outer edge 26 a substantial distance inwardly of outer edge 23.

Each of said holding members 14 has a lower portion 27 attached to and covering the undersurface of middle portion 24 and having an integral flange portion 28 extending outwardly beyond the curved outer edge 26 of middle portion 24.

In my preferred form I prefer that upper portion 21, middle portion 24 and lower portion 27 of each of my holding members 14 be separate pieces and attached as hereinbefore described for ease in assembly of the parts, yet it is within the contemplation of my invention that my holding member 14 may be made, cast or otherwise formed in a single piece with corresponding portions 21, 24 and 27 being integral portions of the holding member 14.

A padding 29 of non-scratch material such as cotton flocking, soft felt, sponge rubber or any other suitable material is attached to flange portion 28, curved outer edge 26, and the undersurface 30 of upper portion 21.

In use the undersurface 30 of the upper portion of each holding member rests against the top surface 31 of the conventional toilet seat 32, the curved outer edge 26 of middle portion 24 contacts the curved portion 33 of the seat 32 and the flange portion 28 of the lower portion 27 bears against the undersurface 34 of the seat 32. This arrangement provides for a non-slip fit between the baby's seat 10 and the larger seat 32, as the baby sits on the baby's seat 10, the downward pressure tends to force the flange portion 28 upwardly against the undersurface 34 to hold the seats in fixed position. This accurate fit cooperates with the padding 29 to prevent scratching and marring of the seat 32.

The hinges of my holding members are so positioned and my seat 10 is of such a size that my seat 10 may be easily positioned on and simply withdrawn from seat 32. By the mere pivoting of either one of the holding members 14, by slight inward movement on the outer edge 35 of lower portion 27 the other holding member may be moved inwardly, and the seat 10 removed from seat 32.

Having thus described my invention, I claim:

1. An infant's toilet seat comprising a seat portion having an opening therein, a pair of gripping members hingedly attached to opposite sides of the undersurface of said seat portion, each of said gripping members having a curved middle portion, and flanges on either side of said curved portion, said gripping members adapted to pivot to removably position said infant's toilet seat on a conventional large size toilet seat having a seat portion with a curved opening, the curved middle portion of said gripping members contacting the curved portion of said conventional seat and the flanges contacting the upper and under surfaces of said conventional seat.

2. An infant's toilet seat comprising a seat portion having an opening therein, a pair of gripping members hingedly attached to opposite sides of the undersurface of said seat portion, each of said gripping members having a curved middle portion, and flanges on either side of said curved portion, said gripping members adapted to pivot to removably position said infant's toilet seat on a conventional large size toilet seat having a seat portion with a curved opening, the curved middle portion of said gripping members contacting the curved portion of said conventional seat and the flanges contacting the upper and under surfaces of said conventional seat.

ping members hingedly attached to opposite sides of the undersurface of said seat portion, each of said gripping members having a middle portion having a curved outer edge, a top portion attached to the top surface of said middle portion and having a flange portion extending outwardly beyond the top surface of said middle portion, and a lower portion attached to the undersurface of said middle portion and having an abbreviated flange portion extending outwardly beyond said middle portion, said gripping members adapted to pivot to removably position said infant's toilet seat on a conventional large size toilet seat having a seat portion with a curved opening, the undersurface of said flange of the top portion of each of said gripping members resting on the top surface of the conventional toilet seat, the upper surface of the flange of the bottom portion of each of said gripping members bearing against the under surface of the conventional toilet seat, and the curved outer edge of the middle portion of each of said gripping members conforming substantially to the curved edges defining the opening of the conventional toilet seat.

RICHARD C. LEWIS.
